UNITED STATES PATENT OFFICE.

KARL LICKHARD, OF NEW YORK, N. Y.

DESIGN FOR A SOUP BOWL.

Application filed November 4, 1927. Serial No. 24,001. Term of patent 3½ years.

To all whom it may concern:

Be it known that I, KARL LICKHARD, a citizen of the United States, residing at New York, in the county of New York, and State of New York, have invented a new, original, and ornamental Design for a Soup Bowl, of which the following is a specification, reference being had to the accompanying drawing, forming part thereof.

The figure is a side elevation of a soup bowl, showing my new design.

I claim:

The ornamental design for a soup bowl, as shown.

KARL LICKHARD.
